UNITED STATES PATENT OFFICE.

EDWARD SABINE RENWICK, OF MILLBURN, NEW JERSEY.

BROODER.

SPECIFICATION forming part of Letters Patent No. 353,968, dated December 7, 1886.

Application filed March 4, 1886. Serial No. 194,045. (No model.)

To all whom it may concern:

Be it known that I, EDWARD SABINE RENWICK, of Millburn, in the county of Essex and State of New Jersey, have made an invention 5 of certain new and useful Improvements in Brooders for Young Poultry; and I do hereby declare that the following, in connection with the accompanying drawings, is a full, clear, and exact description and specification of the 10 same.

This invention is an improvement upon the ventilating-brooder described in the patent granted to me May 6, 1879, No. 215,070, and the object of the improvement is to enable a 15 brooder embodying substantially the same invention to be manufactured at a low cost.

To this end my present invention consists of certain combinations and arrangements of devices which are recited in detail in the 20 claims at the close of this specification.

In order that the said invention may be fully understood, I have represented in the accompanying drawings and will proceed to describe the best form in which I have thus 25 far embodied my invention for practical use.

Figure 1 of the said drawings represents a top view of a brooder for young chickens. Fig. 2 represents a top view of the same with the brood-cover removed. Fig. 3 represents 30 a transverse section of the same at the line xx of Fig. 1. Fig. 4 represents a transverse section of the same at the line yy of Fig. 1. Fig. 5 represents a horizontal section of the brooder at the line zz of Fig. 3. Fig. 3* represents a 35 transverse section of the brooder corresponding with that of Fig. 3, but with the lower end of the cold-air tubes communicating with the air outside the body of the brooder.

The body D of the said brooder, which also 40 forms the lamp-chamber or furnace, is of box form, and is covered at its top by a plate of sheet-iron, m , which forms the under side of the hot-air chamber C . The four sides of this hot-air chamber are inclosed by strips a , and 45 its top is formed by the brood-floor G . The brood-floor is formed of thin boards—say, one-half inch thick—so that it is a poor conductor of heat, and the brood-cover E is supported upon this floor by means of four standards, b . 50 The lamp H , by means of which the brooder is heated, is set in the body of the brooder beneath the sheet-iron bottom m of the hot-air

chamber, the lamp being introduced into the body of the brooder through an opening, d , formed in one of the sides thereof for that 55 purpose. The fumes from the lamp are permitted to escape through orifices e , formed in the sides of the body D , beneath the bottom m of the hot-air chamber. The rim of the brood-cover E has a curtain, f , suspended from it to 60 inclose the brood-chamber A , the said curtain being slit at intervals, to enable the chickens to pass readily to and from the brood-chamber.

In order that the brood-chamber may be ventilated with warm air, the brood-floor G is perforated with holes s , to permit warm air to rise from the warm-air chamber C beneath, these holes constituting outlets for said warm air, and in order that the external or cool air may 70 have access to the hot-air chamber the sheet-metal plate forming its bottom is perforated with one or more holes or inlets, $r r$. These cold-air inlets r are arranged to discharge air into the hot-air chamber C close to the position of the lamp H , which position is thus the most heated part of said chamber, and the 75 warm-air holes or outlets s of the brood-floor G are arranged at a distance from the position of the lamp or hottest part of said hot air chamber. This relative arrangement of the cold-air inlets and the warm-air outlets is a distinguishing characteristic of my present invention, and is important, because in the said 80 brooder the brood-floor is heated from beneath, and, being a conductor of heat, (although a poor one as compared with metal,) is hot at its upper side, where the chickens squat or stand upon it, and by reason of the said arrangement the cold air enters the hot-air chamber at or near the most heated part thereof, 85 and rising against the under side of the brood-floor G prevents the latter from being heated as hot as it otherwise would be in consequence of its proximity to the position of the lamp or 90 to the most heated part of the bottom of the hot-air chamber. On the other hand, the current or currents of air in the hot-air chamber flow (as indicated by the arrows in Figs. 2 and 4) from the vicinity of the lamp at H , or the 95 most heated part of the bottom of the hot-air chamber, toward the sides of the brood-chamber, and consequently the outer portions of the floor of the brood-chamber are heated hotter

than they would be if currents of external air were caused to pass from the sides of the hot-air chamber toward the most heated part thereof and had an outlet there, as has been effected in brooders made previous to my present invention. The practical result of the arrangement is that the brood-floor is more equally heated than it would be by the reverse arrangement of cold-air and hot-air openings, 5 the heat of the brood-floor over the lamp being cooler and the heat of its outer portions being warmer than they would be by a reverse arrangement of the hot-air outlets and cold-air inlets.

10 In order that the fumes of the lamp may be kept out of the hot-air chamber, the cold-air inlets in the bottom of the hot-air chamber are fitted with tubes *l*, whose lower ends are preferably near the bottom of the body or furnace 15

20 D, and in order that the current of air through the holes of the perforated brood-floor G and into the brood-chamber C may be increased, or that the hot air may be directed to the brood-cover E, the outlet-holes in the brood-floor G are fitted with upright tubes *t*.

25 The brooder above described may be set with its brood-floor on the same level with the floor of the chicken-run; or the brooder may be set upon the floor of the run, and an inclined walk, K, may be provided, to permit the chickens to pass from the brood-floor G to the floor of the chicken-run. This inclined walk K may be removable and so placed as to cover the opening *d*, through which the 30 lamp is introduced. If the inclined walk is not so placed, the said opening should be closed by a door, and holes for the entrance of air should be made in the sides of the body, at or near the lower edges thereof.

35 In practice I find it expedient to make the brood-floor about three feet square, and the brood-cover two feet square. I also find it expedient to use two cold-air inlet-tubes, *l*, each about one and one-fourth inch in diameter, and to use four warm-air-outlet tubes, *t*, each about one inch in diameter. I also prefer to use a lamp-burner which will burn 40 without a chimney, as this variety of lamp-burner permits the brooder to be made of less 45 height than when a lamp-burner with a chimney is used.

The capacity of the brooder may be doubled by making the brood-floor and brood-cover in the form of parallelograms, the former about three feet wide by five feet long, 50 and the brood-cover being about two feet wide by four feet long, in which case two lamps

should be used, their burners being separated by a space of about two feet, and a set of cold-air-inlet and warm-air-outlet tubes should be applied for each lamp, the relative arrangement of inlets and outlets being substantially the same as previously described, the inlets for cold air being at the two most heated parts of the metal sheet in the vicinity of the two lamps, and the outlet-tubes being distant from them.

Although I prefer to use thin boards as the poor heat-conducting material for the brood-floor, the invention is not limited to a board floor, as the brood-floor may be made of two thicknesses of sheet-iron separated by a space which may be filled with earth or sand; or the floor may be made in the form of a tray, which may be filled with sand.

75 I claim as my invention—

1. The combination, substantially as before set forth, of the brood-floor of poor heat-conducting material, the hot-air chamber beneath the said brood-floor, the cold-air inlet to said chamber, arranged in the vicinity of the most heated part thereof, and a warm-air outlet of said chamber, arranged at a distance from the most heated part of said chamber.

2. The combination, substantially as before set forth, of the brood-floor of poor heat-conducting material, the hot-air chamber beneath said brood-floor, and the cold-air inlet to said hot-air chamber, arranged in the vicinity of the most heated part thereof and fitted with 90 a tube.

3. The combination, substantially as before set forth, of the brood-floor of poor heat-conducting material, the hot-air chamber beneath said brood-floor, and the warm-air outlet from 95 said hot air chamber, arranged at a distance from the most heated part thereof and fitted with a tube.

4. The combination, substantially as before set forth, of the brood-floor of poor heat-conducting material, the brood-cover above the said brood-floor, the hot-air chamber beneath the said brood-floor, the cold-air inlet to said hot-air chamber, arranged in the vicinity of the most heated part thereof, and a warm-air 105 outlet from the said chamber, arranged at a distance from the most heated part thereof.

In witness whereof I have hereto set my hand this 2d day of March, A. D. 1886.

EDWARD SABINE RENWICK.
